UNITED STATES PATENT OFFICE.

EVERETT R. BURTNELL, OF LOS ANGELES, CALIFORNIA, ASSIGNOR OF ONE-HALF TO
HOMER A. BRUNELL, OF LOS ANGELES, CALIFORNIA.

INTERNAL-COMBUSTION ENGINE.

Application filed May 19, 1923. Serial No. 640,167.

To all whom it may concern:

Be it known that I, EVERETT R. BURTNELL, a citizen of the United States, residing at Los Angeles, in the county of Los Angeles 5 and State of California, have invented certain new and useful Improvements in Internal-Combustion Engines, of which the following is a specification.

My invention relates to internal combustion engines of the two stroke cycle type, and 10 has for its principal objects, to generally improve upon and simplify the construction of the existing forms of the two stroke cycle engines and to provide an engine that has a 15 relatively short overall length and in which two power impulses are produced for each complete rotation of the crank shaft.

Further objects of my invention are to 20 provide a two stroke cycle internal combustion engine unit of six cylinders arranged in two series of three cylinders each with the two series co-operating with each other to produce a maximum of engine efficiency, and 25 to provide a two stroke cycle engine structure in which the six cylinders that compose the engine unit are functioned in power transmission, and gaseous fuel pumping effect by two crank throws of a single crank shaft.

30 A still further object of my invention is, to provide an engine of the character referred to, wherein two of the cylinders of each set or series of three cylinders, are formed at the head end with a clearance common to 35 both cylinders and the third cylinder of the set of three, functioning as a pumping cylinder and together with the two connected cylinders, being disposed radially in a plane substantially at right angles to the axis of 40 the crank shaft, in line with the center of the throw or crank of the crank shaft, to which the pistons of the three cylinders forming a radial structural unit are connected.

With the foregoing and other objects in 45 view, my invention consists in certain novel features of construction and arrangement of parts that will be hereinafter more fully described and claimed and illustrated in the accompanying drawings in which:

50 Fig. 1 is a transverse vertical section taken lengthwise through the centers of a set of three cylinders that form one of the units of my improved engine.

Fig. 2 is a horizontal section taken approximately on the line 2—2 of Fig. 1. 55

Fig. 3 is a side elevational view of the crank shaft.

Referring by numerals to the accompanying drawings, 10 and 11 designate respectively the upper and lower parts of the 60 crank case, the end walls thereof being provided with suitable bearings for a shaft 12 having two throws or cranks 13 and 14.

Secured to the upper portion of the crank case, member 10 and in the same radial plane 65 with the center of crank 13 are two cylinders 15 and 16 that are angularly disposed with respect to each other so that their axes are radially arranged relative to the crank shaft 12. 70

Cylinder 16, which is the second cylinder in the direction of crank shaft rotation occupies a substantially vertical position directly above the axis of the crank shaft and cylinder 15, which is the first cylinder in the 75 direction of crank shaft rotation occupies an angular position immediately to the side of said cylinder 16.

The upper portions of cylinders 15 and 16 are connected by a head 17, either separately formed or integral, as illustrated and 80 a chamber 18 in said head connects the clearance 19 in cylinder 15 with the clearance 20 in cylinder 16.

Thus chambers 18, 19 and 20 constitute a 85 common compression, combustion and expansion chamber inasmuch as the gaseous fuel inducted into said chamber, is compressed, ignited and expands therein.

The upper portion of the walls of the cylinders 15 and 16 and the wall of head 17 are provided on their external surfaces with heat radiating fins 21, and seated in head 18 preferably above clearance 20 is a suitable ignition device, preferably a spark plug 22. 90

Cylinders 15 and 16 are provided respectively, with interiorly arranged open-ended sleeves 23 and 24 that serve as liners or piston bearings.

Formed through the intermediate portion 100 of cylinder 15 and its lining 23 is a circumferential row of exhaust ports 25 and the 105 portion of said ports is such, that they are wholly uncovered and open, only when the piston 26, that reciprocates in chamber 19, is at the lower end of its stroke or travel.

Formed in the intermediate portion of cylinder 16 and its lining sleeve 24 is a series of gaseous fuel inlet ports 27, that are located so that they are wholly uncovered and open, only when the piston 28, that reciprocates in chamber 20, is at the lower end of its stroke or travel.

Piston 28 is connected in the usual manner to crank 13 by a connecting rod 29 and connecting piston 26 to the lower portion of said rod 29 is a connecting rod 30.

Thus the pistons 26 and 28 that operate in the cylinders 15 and 16 are practically connected to the same crank of the crank shaft, but owing to the relative angular positions of the cylinders and the slight offset between the axis of the pivot between the lower end of rod 30 and rod 29 and the axis of crank 13, piston 26 travels slightly in advance of piston 28.

Thus the exhaust ports 25 that are controlled by piston 26, start to open an instant before inlet ports 27 that are controlled by piston 28 start to open and, likewise said exhaust ports are fully closed an instant prior to the full closing of said inlet ports.

Located directly behind cylinders 15 and 16 and in line longitudinally therewith, are the cylinders 15^a and 16^a of the second set 30 or series of cylinders of the engine, and these last mentioned cylinders are identical in size, form and construction with said cylinders 15 and 16.

The piston (not shown) within cylinder 16^a is connected to crank 14 by a connecting rod 31 and the piston (not shown) within cylinder 15^a is connected by a rod 31^a to the lower portion of said connecting rod 31.

Arranged in the top of crank case member 40 10 and to the side of cylinder 16 is a precompression or pumping cylinder 32 that occupies an angular position so that its axis is radial with respect to crank shaft 12.

This cylinder occupies the same radial 45 plane with the cylinders 15 and 16 and a piston 33 that reciprocates within said cylinder is connected by a rod 34 to the lower portion of connecting rod 29.

Formed through the intermediate portion 50 of the wall of cylinder 32 is a series of gaseous fuel inlet ports 35 and communicating therewith is an annular duct 36 that is connected to a suitable source of gaseous fuel supply, preferably a carburetor.

The ports 35 are located so that they are wholly uncovered only when piston 33 is at the lower end of its stroke.

The wall around the upper portion of the cylinder 32 is provided with a chamber 36^a 60 through which may be circulated the hot gases and products of combustion that discharge from ports 25.

Located in the upper crank case member 10 adjacent to cylinder 32 and in the same 65 radial plane with the cylinders 15^a and 16^a,

is a cylinder 32^a that is identical in size, form and construction with said cylinder 32.

The piston (not shown) within this cylinder 32^a is connected by a rod 37 to the lower portion of the connecting rod 31.

Thus the pistons in the first radial row or series of cylinders are connected to crank 13, and the pistons in the second or rear radial row of cylinders are connected to crank 14.

Leading from the upper portion of pre-compression cylinder 32 to the inlet ports 27 in cylinder 16 is a duct 38, and leading from the upper portion of cylinder 32 to the inlet ports in cylinder 16^a is a similar duct 39.

Thus, pumping cylinder 32 functions for the combustion cylinders 15^a and 16^a and the adjacent pumping cylinder 32^a functions for the combustion cylinders 15 and 16.

The operation of my improved engine is as follows:

Inasmuch as cranks 13 and 14 are disposed 180 degrees apart, the pistons 26, 28 and 33 in the first cylinder unit of the engine will be at the lower ends of their travel when the pistons in the cylinders 15^a, 16^a and 32^a 90 are at the upper ends of their travel and vice versa.

When pistons 32 and 32^a are at the lower ends of their travel, the gaseous fuel ports, such as 35 in the pumping cylinders are 95 wholly opened, thereby admitting gaseous fuel into the piston clearance chambers within said cylinders.

As the pistons in the pumping cylinders move upwardly therein, the gaseous fuel will 100 be precompressed in the upper portion of said cylinders and at the same time the gaseous fuel will be heated by the heated exhaust gases passing through the chamber 36^a.

Due to the cross-over arrangement of the ducts 38 and 39, pumping cylinder 32 functions to pump compressed gaseous fuel into the cylinders 15^a and 16^a and cylinder 32^a 110 functions to pump compressed gaseous fuel into the cylinders 15 and 16.

Exhaust ports 25 and inlet ports 27 are open at the same time, but with said exhaust ports opening slightly before the opening of said inlet ports and as the latter are opened the charge of gaseous fuel from cylinder 32^a will pass through duct 38 and inlet ports 27 into chamber 20 and the rush of this gaseous fuel will drive before it practically all the products of combustion from the preceding ignited charge and said products of combustion will be forced through chambers 18 and 19 out through the exhaust ports 25.

As the pistons 26 and 28 move upward in their respective cylinders, the gaseous fuel charge that practically fills the chambers 18, 19 and 20 will be compressed within said chamber 18 and, as the pistons 26 and 28 pass their high centers or immediately there-

after the compressed charge of gaseous fuel will be ignited by a spark produced by plug 22 and the expansion following combustion will drive said pistons downward on their 5 power stroke.

Inasmuch as the pistons in the two sets of combustion cylinders work, or travel directly opposite to each other, it will be seen that the crank shaft of the engine receives two 10 power impulses during each complete rotation and as a result, a relatively high degree of crank shaft power is developed.

Thus it will be seen that I have produced a two stroke cycle internal combustion engine that is of relatively simple structure, 15 very short in overall length, devoid of all valves and their operating mechanisms, and said engine being composed of relatively few parts which may be of strong, rugged construction, therefore making it adaptable for 20 a wide variety of purposes.

Obviously the size, form and construction of the various parts of my improved may be made and substituted for those herein described without departing from the 25 spirit of the invention, the scope of which is set forth in the appended claims.

I claim as my invention:

1. A two stroke cycle internal combustion engine having six cylinders arranged in two 30 radial rows with three cylinders in each row, two cylinders in each row functioning as combustion cylinders and the third cylinder in each row functioning as a gaseous fuel precompression and pumping cylinder.

2. A two stroke cycle internal combustion engine having six cylinders arranged in two radial rows with three cylinders in each row, 40 two cylinders in each row functioning as combustion cylinders, the third cylinder in each row in the direction of crank rotation functioning as a gaseous fuel precompression and pumping cylinder, a crank shaft having two cranks, pistons arranged for operation in all of the cylinders, the pistons in one row of cylinders being all connected to one crank of the crank shaft and the pistons in the 45 other row of cylinders being all connected to the other one of the cranks of the crank shaft.

3. An internal combustion engine having 50 six cylinders arranged in two radial rows of three cylinders each, the first and

second cylinders in each row in the direction of crank rotation being joined at their head ends by a compression clearance common to the chambers in both of said cylinders, there being ports formed in the walls 60 of all of the cylinders, the ports in the first cylinder in each row in the direction of crank rotation being adapted to function for the exhaust of products of combustion from the first and second cylinders in the direction of crank rotation in the respective rows, the ports in the second cylinder of each row functioning for the admission of gaseous fuel to the first two 65 cylinders in the direction of crank rotation in the respective rows, and the third or last cylinder in each row functioning for the precompression and pumping of gaseous fuel for the induction function into the second cylinder of the other or opposite radial row of cylinders.

4. An internal combustion engine having six cylinders arranged in two radial rows of three cylinders each, the first and second cylinders in each row in the direction 70 of crank rotation being joined at their ends by a compression clearance common to the chambers in both of said cylinders, there being ports formed in the walls of all of the cylinders, the ports in the first cylinder in each row in the direction of crank rotation being adapted to function for the exhaust of products of combustion from the first and second cylinders in the direction of crank rotation in the respective 75 rows, the ports in the second cylinder in the direction of crank rotation in each row functioning for the admission of gaseous fuel to the first two cylinders of the respective rows and the third or last cylinder in each row functioning for the precompression and pumping of gaseous fuel for the induction function into the second cylinder of the other or opposite radial row of cylinders, pistons arranged for operation within all of the cylinders of the two rows, a shaft having two cranks, each being in line with the axes of the cylinders in one radial row and connections between the pistons in the two rows of cylinders and the respective cranks.

In testimony whereof I affix my signature.

EVERETT R. BURTNELL.
